Primary Examiner — Aula Soroush(74) *Attorney, Agent, or Firm* — Jeenam Park(57) **CLAIM**

The ornamental design for an animal training device, as shown and described.

DESCRIPTION

FIG. 1 is a perspective view of an animal training device, showing my new design;

FIG. 2 is a perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlargement detail view of FIG. 1; and,

FIG. 10 is an enlargement detail view of FIG. 2.

The dot-dash broken lines represent the boundary of the enlarged portion and form no part of the claimed design.

1 Claim, 10 Drawing Sheets(56)
